ROTARY FLUID PRESSURE DEVICE

Charles M. Kendrick, New York, N. Y., assignor
to Manly Corporation, Washington, D. C., a corporation of Delaware

Application March 28, 1938, Serial No. 198,449

20 Claims. (Cl. 121—87)

This invention relates to vane type rotary fluid pressure devices and particularly to vane type fluid motors in which the rotor is provided with a plurality of vanes arranged to move inwardly and outwardly thereof, for example, in a substantially radial direction, during the operation of the device.

Fluid motors of this general class find their widest use at present as hydraulic devices, that is, devices for handling or whose motive fluid is a liquid, such, for example, as oil, and the motor of the present invention will be described in connection with such use. It will be understood, however, that the invention is applicable to motors operating with elastic fluids.

Vane type motors of this character are provided with a vane track which is adapted to contact the exposed ends of the vanes and to guide and control their inward and outward movement. It is essential that cooperating contact between the vanes and the vane track be maintained in order to obtain smooth, quiet and satisfactory operation of the device.

In devices of this kind when operated as pumps, it is customary to depend upon and to utilize the centrifugal force brought about by the rotation of the rotor to force the vanes radially outward and maintain contact between their ends and the vane track. In some cases the action of centrifugal force is supplemented by introducing behind the inner ends of the vanes fluid from the discharge or high pressure chamber of the pump. The added hydraulic force cannot become effective, however, until the pump begins to operate and builds up pressure in its discharge chamber so that when the pump is started centrifugal force alone is available to move the vanes outward. In either case, therefore, the pump does not begin to deliver fluid until the speed of its rotor is sufficient to produce the centrifugal force required to effect some radially outward movement of the vanes.

Vane type pumps of this general class have met with marked commercial success for supplying fluid under pressure to operate the numerous hydraulically actuated devices now in wide industrial use. The necessity of relying on centrifugal force to produce outward movement of the vanes has, however, limited their use to applications in which the rotative speed is sufficient to produce the necessary centrifugal force.

In contrast to the popularity of radial vane type pumps, radial vane type fluid motors have not heretofore been commercially successful, although such motors have many of the same ad-

vantages as radial vane type pumps, such as low cost, simplicity, compactness, etc. The reason for this is that fluid motors are called upon to operate under conditions not usually encountered by pumps and which previous radial vane type pumps and motors are incapable of meeting successfully. A fluid motor, for example, is subject to frequent stopping and starting during its operation, whereas a pump is usually kept running continuously and at a relatively high speed while in use. A fluid motor must start under full load, which is not required of radial vane type pumps as now employed. A motor must also operate under full load at speeds which never become high as well as in accelerating and decelerating to and from relatively high speeds, whereas a radial vane type pump does not begin to operate until its rotor has attained considerable speed, as already explained. In other words, a vane type fluid motor must operate satisfactorily under circumstances in which there is insufficient centrifugal force acting on its vanes to bring about the necessary contact between them and its vane track.

This condition is aggravated in a radial vane type motor, as compared to a radial vane type pump, because the operating fluid under operating pressure in contact with the exposed ends of the motor's vanes acts to force them radially inward at the very time these vanes must move radially outward, that is, during intake, which is not the case in such a pump. Introduction of the operating pressure fluid behind the inner ends of the vanes will act to balance the hydraulic force pushing the vanes inward, but results obtained by this expedient are not satisfactory in so far as vane motors are concerned.

Radial vane type motors constructed in the same manner as the usual radial vane type pump either will not start (the fluid merely by-passing through the motor) or will start with an abrupt jerk. Jerky, noisy and uneven operation continues throughout the operation of the motor at low rotative speeds, and will continue indefinitely until and unless a speed is reached at which sufficient centrifugal force is produced to effect the necessary contact between the vanes and vane track. This type of operation renders such a vane motor impractical and unsuited for commercial use.

Numerous attempts have been made to overcome this difficulty and to provide means for making a radial vane type fluid motor operate satisfactorily. As far as I am aware, none of these have proved practical or commercially ac-

ceptable. It has been suggested, for example, that a spring be placed behind the inner ends of the vanes to urge them outward but limitation of space and other constructional and operating difficulties have heretofore rendered this scheme impractical.

The principal object of this invention is to overcome the above-mentioned difficulties and provide an improved vane type fluid motor capable of starting smoothly at full load and of operating smoothly and satisfactorily at low rotational speeds at full load as well as at higher speeds.

Other and more specific objects will appear from the description which follows.

The invention will be understood from a consideration of the accompanying drawings which illustrate, by way of example, the invention as embodied in a fluid motor in which the vanes move outwardly and inwardly of the rotor in a substantially radial direction.

In the accompanying drawings:

Fig. 1 is a view, partly schematic, showing a side elevation of a fluid motor and its connections according to the present invention;

Fig. 2 is an enlarged longitudinal sectional view taken through the vertical center line of the motor shown in Fig. 1;

Figs. 3 to 7 are sectional views transverse the axis of rotation of the rotor drawn to the same scale as Fig. 2 and in which:

Fig. 3 is taken along the line 3—3 of Fig. 2 looking in the direction of the arrows, showing the rotor and its vanes and other parts of the fluid motor;

Fig. 4 is a view taken along the line 4—4 of Fig. 2, corresponding to Fig. 3 but looking in the opposite direction as indicated by the arrows and showing the rotor side of the cover end plate and cover;

Fig. 5 is a view along the line 5—5 of Fig. 2, showing the parts as viewed with the cover end plate in place but with the cover removed;

Fig. 6 is a view taken along the line 6—6 of Fig. 2 showing the side or face of the casing end plate, adjacent the side wall of the cavity in the casing;

Fig. 7 is a view taken along the line 7—7 of Fig. 2, showing the fluid channels and their connections;

Fig. 8 shows a modification of the cover end plate;

Fig. 9 is a view, partly schematic, corresponding generally to Fig. 1 but showing a modification;

Fig. 10 shows a further modification of the invention; and

Fig. 11 shows the connections for the insertion of a reversing valve.

Referring first to the embodiment of the invention illustrated in Figs. 1 to 7 of these drawings, as shown in Fig. 2, the motor includes a casing 10 and cover 11 which cooperate to form a cavity for the usual rotor 15 and associated parts. The rotor 15 is formed with a pair of hubs 16 by which it is rotatably supported in a pair of bushings 17 carried by the casing 10 and cover 11 respectively. The rotor has a plurality of vanes 19 which are movable in a substantially radial direction inward and outward in the vane slots 18.

The motor shaft 22 is revolvably supported upon a pair of bearing members 23 carried by the casing 10 and cover 11 respectively and passes through the central bore of the rotor 15, with

5 which it has a slidably splined connection as at 21 (Figs. 3 and 4). One end of the shaft 22, shown as broken off in Fig. 2, projects outward beyond the casing 10 for connection to the apparatus to be operated by the motor.

A vane track ring 25 (Figs. 2 and 3) surrounds the rotary assembly and its inner circumferential surface 26 forms a track adapted to contact the outer ends of the vanes 19; for convenience this surface 26 will be termed the "vane track." The vane track 26 is of variable diameter but its curvature is preferably symmetrical on either side of a line passing through the center of the rotor 15.

15 The motor here illustrated is of the hydraulically balanced "double acting" type of hydraulic device in which each vane is reciprocated twice for each revolution of the rotor. As shown in Fig. 3 the space intermediate the periphery of the rotor 15 and the vane track 26 is accordingly divided into two fluid sections by means of two sealing areas or chambers formed by cooperation of the rotor 15 and the ends of the vanes 19 with the vane track 26 at the region of the vane track's least diameter, which in this instance is adjacent the horizontal center line. The vane track 26 is preferably provided at each of these points of division (sealing areas or chambers) with a sealing arc 27 substantially concentric with the rotor 15 and extending in a circumferential direction for a distance equal at least to the angular distance between a pair of adjacent vanes 19, in order that there shall be substantially no radial movement of the vanes 19 while passing thereacross.

25 Each fluid section includes a working space, or chamber, 31 (Fig. 3) flanked by an inlet area 29 and an outlet area 30, fluid being admitted to the inlet area 29 by a port, or slot, 36 at one side 30 of the rotor, and led away from outlet area 30 by a similar port, or slot 37. Fluid is thus admitted to the spaces between the vanes as they move through the inlet area 29 toward the working space 31. Each working space or chamber 31 is located at the region of the greatest diameter of the vane track 26, and extends circumferentially between the adjacent ends of the inlet and outlet slots 36 and 37, and for an arcuate distance substantially equal to but not less than the distance between two adjacent vanes 19. Each fluid inlet area 29 is thus at all times radially separated from the fluid outlet area 30 of the same fluid section by at least one of the vanes 19 in cooperation with the vane track 26 and the difference in fluid pressure on the opposite side 50 faces of such vanes causes the rotation of the rotor. Fluid is discharged into the outlet slots 37 as the vanes recede from the working spaces.

55 The surface of the vane track 26 within the working spaces 31 is preferably concentric with rotor 15 and that intermediate the sealing arcs 27 and the working spaces is given any suitable curvature producing satisfactory rates of inward and outward movement of the vanes 19 as the rotor revolves.

60 The sides or axial ends of the working spaces, the fluid inlet areas 29 and the fluid outlet areas 30 are defined by a pair of disc-shaped members 34 and 35 (Fig. 2) for convenience termed "end plates," which are provided with holes at their centers through which pass the hubs 16 of the rotor 15. The outer surfaces of the end plates 34 and 35 fit snugly against the adjacent wall surfaces of the casing 10 and cover 11 respectively and form substantially fluid tight fits with

the several ports and passages to be presently described. The inner or opposing faces of the end plates 34 and 35 form fluid tight fits with the sides of the vane track ring 25 by which they are axially positioned with respect to the rotor 15 in such manner that the rotor is permitted to turn freely while its sides and the sides of the vanes 19 form substantially fluid tight running fits with the adjacent faces of the end plates 34 and 35. The end plate 34 will hereinafter be termed the "casing end plate" and similarly the end plate 35 will be termed the "cover end plate."

Each of the end plates 34 and 35 is formed with two pairs of arcuate slots 36 and 37 respectively as shown in Figs. 3 to 6. The slots 36 in the casing end plate 34 serve as the inlet ports for the fluid inlet areas 29 and the slots 37 in the same end plate serve as outlet ports for the fluid outlet areas 30. Each slot 36 of the casing end plate 34 and its connected inlet area forms an inlet chamber and each slot 37 of said casing end plate 34 and its connected area an outlet chamber.

The fluid circuit of the motor includes a fluid inlet channel 40 (Figs. 2 and 7) and a fluid outlet channel 41. The fluid inlet channel 40 is appropriately connected with a fluid inlet passage or pipe 42 (Figs. 1, 2 and 7) and is also appropriately connected with the fluid inlet ports or slots 36 in the casing end plate 34 as indicated by the dotted lines of Fig. 7. The fluid outlet channel 41 is similarly connected with the outlet or discharge pipe 43 and with the fluid outlet ports or slots 37 in the casing end plate 34.

With the parts in the position shown in Fig. 3, fluid under operating pressure entering the fluid inlet ports 36 will produce clockwise rotation of the rotor and shaft 22. In order for operation to take place, however, it is necessary that the vanes 19 which separate the fluid inlet areas 29 from the fluid outlet areas 30 at the working spaces 31 be firmly in contact with the vane track and that there be similar contact between the ends of the vanes 19 and the vane track at arcs 27 of the horizontal points of division between the two fluid sections. It is also important and substantially essential for quiet operation that contact between the vanes 19 and the vane track be maintained throughout the movement of the vanes 19 through the fluid inlet areas 29, as sudden and abrupt outward movement of the vanes would otherwise result and would produce noise, wear and unsatisfactory operation. But as already explained, this contact of the vanes 19 at the sealing arcs 27 and working spaces 31 and the track-following action of the vanes 19 as they pass through the fluid inlet areas 29 will not dependably result at starting or at low rotative speeds unless the vanes 19 are acted upon by an adequate radially-outward force. According to the present invention, this force is produced and brought to bear on the vanes by improved means for introducing behind the inner ends of the vanes fluid having a controlled pressure higher than that of the fluid in the fluid inlet areas 29. The means employed for this purpose will now be described.

As shown in Figs. 3 to 7, the end plates 34 and 35 are each formed with two pairs of arcuate recesses or grooves 48 and 49 in the faces thereof adjacent the rotor 15. These recesses 48 and 49 are positioned to register with the inner ends of the vane slots 18 as the rotor revolves and they act as ports or passageways for fluid to and from

said vane slots 18 and hence are termed "vane slot ports."

The vane slot ports 48 are of such length and are so positioned that, as the rotor revolves, they register and connect with the inner end of each vane slot 18 from the time that the outer end of the vane 19 therein reaches the point on the sealing arcs 27 where the vanes 19 act to separate the two fluid sections of the motor. The vane slot ports 48 are coextensive with the fluid inlet areas 29 and conveniently also with the working spaces 31; that is to say, in this embodiment the vane slot ports 48 connect with the inner end of each vane slot 18 during the time that the vane 19 therein is passing across the corresponding sealing arc 27 through the fluid inlet area 29 and during the entire time it is traversing the working space.

In order that the vane slot ports 48 may receive a supply of fluid, the vane slot ports 48 in the cover end plate 35 are connected with the branched ends of a pipe 52, as shown in Figs. 1 and 2. The fluid connections between each of the vane slot ports 48 in the cover end plate 35 and its branched end of the pipe 52 include a hole drilled through the cover end plate 35 (Figs. 2 and 5) which connects said vane slot port 48 with a groove 50 (Figs. 2, 4 and 5) recessed in the outer face of the cover end plate 35, that is, the face adjacent the wall surface of the cover 11. Each groove 50 registers with a passage 51 extending through the cover 11 to which its end of the branched pipe 52 is suitably connected as shown in Fig. 2. In the present embodiment the vane slot ports 48 in the casing end plate 34 are not directly connected with the fluid supply, although they may be so connected, and act principally as "balance ports" to contain a supply of fluid (which is received through the vane slots 18) having the same pressure as the fluid in the vane slot ports 48 of the cover end plate 35, in order to substantially balance the hydraulic forces acting on the sides or axial ends of the vanes 19 and prevent binding of said vanes.

When the pipe 52 is supplied with fluid having a pressure greater than that of the fluid in the inlet areas 29, such greater pressure fluid will pass through the intervening fluid connections into the vane slot ports 48 and into all of the vane slots 18 at the particular instant connected therewith and will force outward against the vane track 26 all of the vanes 19 therein. The pressure of the fluid in the inlet areas depends, however, upon the load, that is, the resistance to rotation presented by the rotor and its connected shaft 22, and this pressure changes as the load changes. The pressure of the fluid in the inlet areas 29 will thus vary through a wide range from a relatively low pressure to maximum, and pressure changes may, and most frequently will, occur suddenly and from time to time during the operation of the motor. If the fluid supplied to the vane slot ports 48 was of a constant pressure, it would therefore be necessary that its pressure at all times exceed the maximum pressure which might at any time exist in the inlet areas 29. The result of this would be that there would frequently be a very great difference between the pressures of the fluid in the vane slot ports 48 and the inlet areas 29, as for example when the motor is operating under light load and the pressure of the fluid in the inlet areas 29 is correspondingly low. For example, if the motor is intended for operation at a maximum pressure of 1,000 lbs. per square

inch in its fluid inlet areas, the fluid supplied to its vane slot ports 48 must, with such an arrangement, always have a pressure in excess of 1,000 lbs. per square inch, even when the pressure of the fluid in the inlet areas is low, such as 100 lbs. or 200 lbs. per square inch.

This condition is highly undesirable because of the losses involved in raising the pressure of the fluid supplied to the vane slot ports 48 to an unnecessarily high amount and also because the vanes 19 in all the vane slots 18 at any instant connecting therewith would be pushed out against the vane track 26 with a relatively great force which would create undue gripping action and tendency for the vanes 19 to bind against the vane track 26, and would also result in increased wear of the parts. In fact, such an arrangement would be impractical whenever the motor is called upon to operate under widely varying loads, as is usually the case, and could be practically used only in the rare circumstances in which the motor's load is substantially constant.

In order to overcome this difficulty, the present invention provides improved means whereby the pressure of the fluid supplied to the vane slot ports 48 is at all times correlated with and exceeds by a substantially constant amount the pressure of the fluid actually existing in the inlet areas 29. This difference in pressures is maintained irrespective of the amount of the pressure in the fluid inlet areas or frequency of change thereof, and the means by which this is accomplished will now be described.

Referring to Fig. 1, the inlet pipe 42 is provided with a valve 60 which includes a valve body 61 slidably mounted in the valve bore therein and which is urged inward toward its fully closed position by a spring 62. The inner end of the valve body 61 is adapted to be acted upon at all times by the pressure of the fluid in the valve's fluid receiving port 63 and is accordingly provided with a small stop 65 to prevent its inner end surface from contacting the closed end of the valve bore when said valve body 61 is in its fully closed position as shown in Fig. 1. The outer end of the valve body 61, which has the same area as the inner end thereof, is similarly adapted to be acted upon by fluid having the same pressure as that in the valve's fluid discharging port 64 and the outer end of the valve bore is accordingly connected with said discharging port 64 as by a passage 66 which enters the valve bore at a point which will not be covered when the valve body 61 is in its fully open position.

When operating pressure fluid is admitted to the inlet pipe 42 it passes first to the valve's receiving port 63 where it acts upon the inner end of the valve body 61 and raises said valve body 61 against the spring 62. This movement of the valve body 61 opens the valve 60 and permits pressure fluid to pass into the valve's discharging port 64 whence it immediately passes into the outer end of the valve bore and acts upon the outer end of the valve body 61. Two oppositely acting forces are thus brought to bear upon the valve body 61, the force tending to move it outward comprising the action of the pressure fluid against its inner end and the opposing force tending to move the valve body 61 inward comprising the force exerted by the pressure fluid acting upon its outer end in combination with the force exerted by the spring 62. The valve body 61 is accordingly moved until the opposing forces balance, in which position it provides an orifice through the bore of the valve 60 of the proper

size to create the necessary difference of pressures of the fluid in the receiving port 63 and discharging port 64 respectively, due to the resistance of flow through said orifice, as determined by the spring 62.

As the areas of the inner and outer ends of the valve body 61 are equal, this balancing of forces acting on the valve body 61 is determined entirely by relative pressures existing in the receiving port 63 and discharging port 64 respectively and is independent of absolute pressures; that is to say, substantially the same difference exists in these pressures regardless of the actual amount of pressure in either of said ports. This difference is therefore maintained substantially constant throughout the entire range of operating pressures. The valve body 61 will also move immediately to compensate for any change in operating conditions, such as variation in the amount of fluid passing into the inlet pipe 42, change in viscosity of the operating fluid, etc.

The pressure of the fluid in the valve's discharging port 64 is, of course, the same as the pressure in the inlet areas 29 of the motor and the intervening fluid connections and, as already explained, is determined by the motor's load. The valve 60 therefore operates to maintain the fluid in its receiving port 63 at a pressure higher by a substantially constant amount than the pressure of the fluid in the inlet areas 29. This difference in pressures is maintained under all operating conditions. The higher pressure in the valve's receiving port 63, and consequently in its connected portion of the pipe 42, is accordingly termed the "differential high pressure." Valve 60 is likewise usually termed a "differential pressure valve," but is also sometimes termed a "pressure reducing valve."

The pipe 52 is connected with the fluid circuit 40 at a point where it will receive the differential high pressure fluid. As shown in Fig. 1, this connection is made with the portion of the fluid inlet pipe 42 which leads to the valve's receiving port 63. The pipe 52 and hence also the vane slot ports 48 thus always receive a supply of the differential high pressure fluid, the pressure differential of which is made sufficient to force outward and to maintain proper contact between the ends of the vanes 19 in all the vane slots 18 which at any instant register with said vane slot ports 48. The inner ends of the vanes 19 are thus supplied with fluid having sufficient pressure to keep them in proper operating position, and the pressure of this fluid is always definitely regulated by a relatively constant difference to the pressure of the fluid acting on the exposed ends of the vanes 19. The amount of this pressure differential is determined by the spring 62 and may be varied by adjustment of the screw 67 (Fig. 1). In practice it has been found that a pressure differential of from about 10 lbs. to 75 lbs. per square inch is usually sufficient and may be varied as conditions require but is preferably kept at the minimum.

Another feature of the arrangement shown in Fig. 1 is that it assures proper contact between the ends of the vanes 19 and the vane track 26 before any pressure fluid is admitted to the fluid inlet areas 29 where it can act upon the exposed ends of said vanes. This is due to the fact that the valve body 61 completely cuts off communication between the portions of the pipe 42 which are connected with the receiving port 63 and discharging port 64 whenever the difference in pressures is less than the amount determined by

the spring 62, as would be true when the motor is not in operation. Thus no fluid can pass through the valve 60 until the pressure in its receiving port 63 (and hence in the vane slot ports 48) rises sufficiently to lift the valve body 61 against the spring 62; that is to say, until the differential high pressure has been established. The vanes 19 will therefore be forced into their proper operating positions a slight time before the operating pressure fluid strikes their outer ends in the inlet areas 28. This is important at starting and assures that the motor will begin to operate promptly, smoothly and quietly.

The operation of the motor is regulated by the amount of pressure fluid admitted to the inlet pipe 42, which may be controlled by any suitable means, not shown. It will be seen from the foregoing that operating pressure fluid entering the pipe 42 will, if the motor is idle, first act to move the vanes 19 outward to their operating positions and that immediately thereafter operating pressure fluid will act against the exposed ends of the vanes 19 at the arcs 31, as already explained, to produce clockwise rotation of the rotary assembly and driven shaft 22, as viewed in Fig. 3. It will also be seen that the differential high pressure acts to maintain proper operating position of the vanes 19 as long as any fluid passes through the valve 60, that is to say, whenever the motor is in operation and at all speeds of its rotor.

Up to this point the operating requirements of the vanes 19 while passing through the outlet areas 30 have not been considered. The ends of the vanes 19 are, of course, exposed only to the relatively negligible pressure of the outlet fluid during this portion of their rotary travel. Upon reference to Fig. 3, it will be seen that the vanes 19 move inward from the time they leave the working chambers 31, while passing through the outlet areas 30 and until their ends reach the sealing arcs 27 at the horizontal points of division between the two fluid sections. The vane track 26 is alone sufficient to produce this inward movement of the vanes 19 but it is necessary to provide means for the escape of fluid contained in the inner ends of the vane slots 18, that is in the portion of the vane slots 18 radially inward of the inner ends of the vanes 19. The vane slot ports 49 in the end plates 34 and 35 (Figs. 3 to 6) are made of such length and position that they register with each vane slot 18 during this portion of the rotary travel of the vane 19 therein and each vane slot port 49 is connected with the fluid outlet areas 30 by means of a groove 53 formed in the outer faces of the end plates 34 and 35 and extending to the arcuate slots 31. Fluid is thus free to pass from the inner ends of the vane slots 18 to the fluid outlet areas 30. This construction has the advantage of reducing the load imposed upon the vane track 26 by the vanes 19 during this part of their travel to substantially that resulting from centrifugal action and from the small force necessary to move the vanes 19 radially inward, thus minimizing power losses and wear.

A fluid motor constructed as hereinbefore described and as illustrated in Figs. 1 to 7 will start promptly and smoothly, will operate evenly and quietly both at relatively low speeds as well as at relatively high speeds. Its parts are simple and require relatively little change from those suitable for use in a vane type pump intended for operation at relatively high speeds only. In

fact the same parts may be employed without change both for such a pump and for this motor except for the modifications in the end plates 34 and 35 and in the cover 11 required to supply the differential high pressure fluid to the vane slot ports 48. A fluid motor constructed according to the present invention therefore enjoys substantially all of the advantages which have contributed to the success and popularity of vane type pumps for operation at relatively high speeds, such as low cost, compactness, simplicity, etc., and may also have the benefits of interchangeability with and joint manufacture of parts for such pumps.

The vane slot ports which connect with the inner ends of the vane slots 18 may be modified in several different ways, as, for example, shown in Fig. 8 which illustrates a modification of the cover end plate. In this instance both end plates are provided with a single, annular vane slot port 148 which continuously connects with all of the vane slots 18. Differential high pressure fluid is supplied to the vane slot port 148 in the cover end plate 135 in the same manner as in the embodiment shown in Figs. 1 to 7. The cover end plate 135 is accordingly formed with a pair of grooves 150 on its outer face which connect with the vane slot port 148 by means of a pair of holes drilled through said end plate 135 and which also register with the fluid passages 51 in the cover 11 to which the ends of the branched pipe 52 are connected.

With this arrangement the differential high pressure fluid is at all times supplied to the inner ends of all the vane slot ports 18 and hence acts continuously throughout their rotation to exert an outward force upon all of the vanes 19. Since the vanes 19 are acted upon by the differential high pressure fluid while their outer ends are passing through the outlet areas 30, the wear and friction on the corresponding portions of the vane track 26 is greater than with the arrangement of Figs. 1 to 7. The construction of Fig. 8 has the advantage of somewhat greater simplicity of manufacture, however, and will also require a smaller volume of differential pressure fluid as the amount of fluid needed to fill the inner ends of the vane slots 18 as the vanes 19 therein move outward while passing across the inlet areas is the same as the quantity of fluid simultaneously displaced from the inner ends of other vane slots 18 while those vanes 19 therein move inward as they are passing across the fluid outlet areas. The volume of differential high pressure fluid therefore need be no more than enough to make up for leakage from the vane slot ports 148 and vane slots 18.

The arrangement shown in Fig. 9 differs from that of Fig. 1 only in the means by which the differential high pressure fluid is obtained. The branched pipe 152 is in this instance connected with the discharge port of a small auxiliary pump 170 which may be driven by any suitable means, not shown, and which is made such that it at all times supplies a quantity of fluid in excess of the amount required by the vane slot ports 48, or 148, as the case may be. The pipe 152 is also connected by a pipe 154 with the fluid receiving port of a small valve 160 whose fluid discharging port is connected by a pipe 155 with the fluid inlet pipe 42.

The valve 160 may be of the same type as the valve 60 of Fig. 1 but is here shown as a pressure relief valve having a spring 162 which urges the ball 161 toward its fully closed position. The

excess fluid not needed by the vane slot ports exhausts through the valve 160 into the pipe 142 and the valve 160 acts to maintain a differential in the pressures of the fluid in the pipes 142 and 152 respectively which is determined by the spring 162. The pressure of the fluid in the pipe 152 and hence in the vane slot ports connected therewith is thus definitely related to the pressure of the fluid in the pipe 142 which is the same as the pressure in the fluid inlet areas 29, and the differential in pressures is continuously maintained.

The inlet port of the pump 170 is preferably connected as by a pipe 171 with the fluid inlet pipe 142, so that its supply of fluid has the same pressure as that of the fluid in said pipe 142. This has the advantage of reducing the work of the pump 170, as it is then necessary for said pump 170 to increase the pressure of the fluid only by the amount of the pressure differential, which is a relatively small amount. This makes it possible to use a less expensive pump than would otherwise be required for this purpose.

The arrangement of Fig. 9 also has the advantage of reducing the volume of fluid raised to the differential high pressure level to only a little more than must be supplied to the vane slot ports in order to obtain proper vane action. This is particularly advantageous when end plates of the type shown in Fig. 8 are used, as the volume of differential high pressure fluid required by them is very small, as already explained. The embodiment of Fig. 9 operates as a fluid motor in the same manner as the motor illustrated in Figs. 1 to 7, which has already been explained.

It sometimes may be desirable to eliminate the differential high pressure fluid after the motor has reached a speed at which the centrifugal action alone is sufficient to produce satisfactory track-following action of the vanes, as for example, when the motor is to be operated uninterruptedly at such relatively high speeds for a long period. An arrangement by which this is accomplished is illustrated in Fig. 10. It is identical with the embodiment of Fig. 1 except for the provision of means for by-passing the operating pressure fluid around the valve 60 and the controls therefor.

In this modification the fluid inlet pipe 242 is provided with a by-pass line 272 having its inlet connection with the inlet pipe 242 at a point between the source of operating pressure fluid (not shown) and the valve 60. The other end of the by-pass line 272 connects with the inlet pipe 242 at a point intermediate the valve 60 and the inlet channel 40 of the fluid motor. Passage of fluid through the by-pass line 272 is controlled by a by-pass valve 273 positioned in said by-pass line 272 and which is of the conventional hydraulically balanced type. The by-pass valve 273 includes a balanced valve piston 274 slidable in the bore thereof and provided with axial passages 275 to provide fluid connection between the portions of the valve bore on each end of the valve piston 274 so that said valve piston 274 will move freely at all times. A return pipe 276 leads from one end of the valve bore through which fluid leaking past the heads of the valve piston 274 may return to the reservoir.

The valve piston 274 is urged toward its fully closed position, in which no fluid is by-passed and in which it is shown in Fig. 10, by a spring 277 and is adapted to be moved in the opposite direction, or toward its fully open position, by

a speed-responsive mechanism, here shown as a conventional centrifugal governor 280. The governor 280 includes the usual governor sleeve 281 which moves upward under centrifugal action of the governor and which is operatively connected as by a pivot 282 with a lever 283, one end of which is fulcrumed on a short link, as at 284. The other end of the lever 283 slidably bears against the outer end of a short rod or plunger 285 which extends through a suitable opening in the closed end of the valve bore and whose other end bears against the valve piston 274. Force exerted by the governor 280 in an upward direction upon the governor sleeve 281 therefore tends to move the valve piston 274 against the spring 277.

The governor 280 is operated at a speed having a fixed relation to that of the rotor of the fluid motor. It is accordingly shown as driven through gearing 286 by the driven shaft 222 of the fluid motor which is made of such length that one end thereof projects through a suitable opening in the motor's cover 211.

The force exerted by the spring 277, which may be adjusted by means of the screw 278, is made sufficient to hold the valve piston 274 in its fully closed position when the motor is idle and against the force exerted thereon by the governor 280 when said governor 280 is operated at speeds corresponding to the relatively low speeds of the rotary assembly at which centrifugal force alone does not produce satisfactory operation of the vanes. Differential high pressure fluid is then supplied to the vane slot ports 48 through the branched pipe 52 and the motor functions in the same manner as the embodiment of Fig. 1.

Increase to relatively high speeds of the driven shaft 222 and of the rotor (at which centrifugal force alone is sufficient to produce satisfactory track-following action of the vanes and differential high pressure fluid is therefore not required) will result in corresponding increase in the speed of the governor 280 and of the force exerted by it on the valve piston 274, so that said valve piston 274 will be moved against the spring 277 toward its fully open position. Operating pressure fluid going to the motor's inlet channel 40 will then be by-passed around the valve 60 so that no differential high pressure of the fluid will be built up. The vane slot ports 48 will be supplied with fluid under substantially the same pressure as that of the operating pressure fluid entering the fluid inlet areas 29, thus effecting balance of the hydraulic forces acting in a radial direction upon the vanes 19 when their outer ends are exposed to operating pressure fluid and holding the vanes 19 against the vane track during the portions of their travel across the arcs 27 and 31 when their outer ends are exposed to fluid under substantially no pressure.

This arrangement, therefore, provides differential high pressure fluid for the inner ends of the vanes during operation of the motor at relatively low speeds at which centrifugal force alone is not sufficient to produce proper track-following vane action and automatically eliminates this differential high pressure at the relatively high speeds of the motor at which it is not needed.

The fluid motor of the present invention is capable of numerous other modifications such as, for example, the arrangement shown in Fig. 11 which illustrates one of several methods by

which the direction of rotation of the rotary assembly and driven shaft may be reversed at will. The fluid motor of this embodiment is identical with that shown in Figs. 2, 3 and 7 except that two end plates of the type illustrated in Fig. 8 are employed.

The direction of rotation of the driven shaft 22 and of the rotary assembly is reversed by the conventional method of reversing the direction of fluid flow. For this purpose the circuit is modified to include a conventional reversing valve 390 through which operating pressure fluid from the valve 60 will pass into the pipe 342 when said reversing valve's rotatable body 391 is in the position illustrated in Fig. 11. The pipe 342 connects with the channel 40 of the fluid motor so that the fluid areas 29 will be the inlet areas and the rotor and driven shaft 22 will be driven in a clockwise direction as viewed in Fig. 3. Fluid exhausted by the motor through the channel 41 will pass out through the pipe 343, the reversing valve 390 and the exhaust pipe 392.

Direction of fluid flow between the reversing valve and fluid motor will be reversed when the rotatable body 391 is rotated 90° in a clockwise direction by a suitable means, not shown. Operating pressure fluid from the valve 60 will then pass into the pipe 343, the channel 41 and the fluid areas 30 (which will then be the inlet areas) and will act to drive the rotor and shaft 22 in a counter-clockwise direction as viewed in Fig. 3. Fluid will be exhausted from the areas 29 (which will then be the outlet areas) through the channel 40 and the pipe 342 which will then be connected through the reversing valve 390 with the exhaust pipe 392.

Differential high pressure fluid will be supplied continuously to the inner ends of all the vanes through the pipe 52, regardless of the direction of rotation of the rotor and shaft 22.

It will be understood that the embodiments of the invention described herein are merely for the purpose of illustrating the invention, and that changes may be made without departing from the spirit of the invention, the scope of which is defined in the appended claims.

I claim:

1. In a rotary vane type fluid pressure device having a rotor including a plurality of vanes movable inwardly and outwardly thereof, a casing therefor including a working chamber and a track for guiding the vanes in their in and out movement, the outer ends of the vanes being subject to the working pressure of the fluid within the working chamber, and means for supplying to the inner ends of the vanes fluid under pressure higher than the pressure in the working chamber thereby urging the vanes into contact with the track independently of the action of centrifugal force, said means comprising a supply line, a power connection leading therefrom to the working chamber, a pressure connection leading from the supply line to the inner ends of the vanes, and a valve in the power connection arranged to cut off communication between the supply line and the working chamber when the motor is not operating and arranged to establish such communication only after a predetermined difference in pressure exists between the supply line and the working chamber.

2. In a rotary vane type fluid pressure device having a rotor including a plurality of vanes movable inwardly and outwardly thereof, a casing therefor including a working chamber and

5 a track for guiding the vanes in their in and out movement, the outer ends of the vanes being subject to the working pressure of the fluid within the working chamber, and means for supplying to the inner ends of the vanes fluid under pressure correlated to and higher than the pressure in the working chamber, thereby urging the vanes into contact with the track independently of the action of centrifugal force, said means comprising a supply line, a power connection leading therefrom to the working chamber, a pressure connection leading from the supply line to the inner ends of the vanes, and a valve in the power connection arranged to maintain a substantially constant differential pressure in the power connection below the pressure in the supply line irrespective of the pressure in the supply line.

3. In a rotary vane type fluid motor having a 10 rotor including a plurality of vanes movable inwardly and outwardly thereof, a casing therefor including a plurality of fluid sections, each fluid section comprising a working chamber and fluid inlet and outlet chambers on either side thereof adjacent the rotor, each working chamber extending for an arcuate distance substantially equal to the distance between two adjacent vanes, tracks for guiding the vanes outwardly while passing through said inlet chambers and inwardly while passing through the outlet chambers, the outer ends of the vanes being subjected to the pressure of the fluid within said respective inlet and outlet chambers as they pass therethrough, and means for supplying to the inner ends of the vanes throughout their rotation fluid under pressure greater than and correlated to the highest pressure within any of said inlet and outlet chambers thereby continually urging the vanes into contact with the track independently of the action of centrifugal force,

40 said means comprising a supply line, a power connection leading therefrom to the working chamber, a pressure connection leading from the supply line to the inner ends of the vanes, and

45 a valve in the power connection arranged to maintain a substantially constant differential pressure in the power connection below the pressure in the supply line irrespective of the pressure in the supply line.

4. In a rotary vane type fluid pressure device 50 having a rotor including a plurality of vanes movable inwardly and outwardly thereof, a casing therefor including a track for guiding the vanes in their in and out movement and provided with fluid inlet and outlet chambers adjacent the rotor whereby the outer ends of the vanes are subjected to the pressure of the fluid within the inlet and outlet chambers as they pass therethrough, means for equalizing the 55 fluid pressure acting on the opposite ends of the vanes which are passing through one of said chambers, and means for supplying to the inner ends of the vanes which are passing through the other of said chambers fluid under pressure higher than and correlated to the pressure of the fluid acting on the outer ends of said vanes, said means comprising a supply line, a power connection leading therefrom to the working chamber, a pressure connection leading from the supply line to the inner ends of the vanes, and a valve in the power connection arranged to cut off communication between the supply line and the working chamber when the motor is not operating and arranged to establish such communication only after a predetermined differ-

ence in pressure exists between the supply line and the working chamber.

5. In a rotary vane type fluid pressure device having a rotor including a plurality of vanes movable inwardly and outwardly thereof, a casing therefor including a track for guiding the vanes in their in and out movement and provided with high pressure and low pressure chambers adjacent the rotor, the outer ends of the vanes being subject to the pressure of the fluid within said chambers as they pass therethrough, means for equalizing the fluid pressure acting on the opposite ends of the vanes while passing through the low pressure chamber, and means for supplying to the inner ends of the vanes during substantially the remainder of their rotary travel fluid under pressure higher than and correlated to the pressure of the fluid acting on the outer ends of said vanes, said means comprising a supply line, a power connection leading therefrom to the working chamber, a pressure connection leading from the supply line to the inner ends of the vanes, and a valve in the power connection arranged to maintain a substantially constant differential pressure in the power connection below the pressure in the supply line irrespective of the pressure in the supply line.

6. In a rotary vane type fluid pressure device having a rotor including a plurality of vanes movable inwardly and outwardly thereof, a casing therefor including a track for guiding the vanes in their in and out movement and provided with two diametrically opposed working chambers, each having high and low pressure chambers on opposite circumferential sides thereof adjacent the rotor, the outer ends of said vanes being subject to the respective pressures within said chambers while passing therethrough, means for supplying to the inner ends of said vanes during substantially their entire passage through the high pressure and working chambers fluid under pressure greater than and correlated to the pressure of the fluid in said chambers, and means for equalizing the pressure on the opposite ends of said vanes while passing through the low pressure chamber.

7. The combination of a rotary vane type fluid pressure motor having a rotor including a plurality of vanes movable inwardly and outwardly thereof, a casing therefor including a track for guiding the vanes in their in and out movement and provided with a working chamber having inlet and outlet chambers on opposite circumferential sides thereof adjacent the rotor, the outer ends of said vanes being subject to the respective pressures within said chambers while passing therethrough, a source of fluid under pressure, means for connecting said source with the inner ends of the vanes during at least a portion of each revolution of the rotor, means including a pressure reducing valve for connecting said source with said inlet chamber, a by-pass valve for the reducing valve and speed-responsive means operated by the motor for opening the by-pass valve when the motor is operating above a predetermined speed.

8. The combination of a rotary vane type fluid pressure device having a rotor including a plurality of vanes movable inwardly and outwardly thereof, a casing therefor including a track for guiding the vanes in their in and out movement and provided with a working chamber having high and low pressure chambers on opposite circumferential sides thereof adjacent the rotor,

the outer ends of said vanes being subject to the respective pressures within said chambers while passing therethrough, an auxiliary pump, means connecting the outlet of said pump to the inner ends of the vanes during at least the portion of their rotary travel in which the vanes are moving outward, the pump delivering pressure fluid at a pressure greater than the pressure in the high pressure chamber and in excess of the amount necessary to insure outward movement of the vanes into contact with said track, outlet means for said excess fluid, and means regulating the passage of the excess fluid through the outlet means to maintain the fluid supplied to the inner ends of the vanes by said pump at a pressure greater than and having a substantially constant relationship to the pressure existing in said high pressure chamber, irrespective of changes in pressure of the fluid in said high pressure chamber.

9. The combination of a rotary vane type fluid pressure device having a rotor including a plurality of vanes movable inwardly and outwardly thereof, a casing therefor including a track for guiding the vanes in their in and out movement and provided with a working chamber having high and low pressure chambers on opposite circumferential sides thereof adjacent the rotor, the outer ends of said vanes being subject to the respective pressures within said chambers while passing therethrough, a pressure fluid line connected with said high pressure chamber, an auxiliary pump connected to receive fluid from said line, means connecting the outlet of said pump to the inner ends of said vanes during at least the time that the outer ends of said vanes are passing through said high pressure chamber, and a pressure valve means connected to return excess fluid delivered by said pump to said line and to maintain the fluid supply to the inner ends of said vanes at a pressure greater than but correlated to the pressure of the fluid in said line.

10. In a rotary vane type fluid motor having a rotor including a plurality of vanes radially movable inwardly thereof, a casing therefor including a track for guiding the vanes in their in and out movement and provided with two diametrically opposed sealing arcs and two diametrically opposed working chambers each having high and low pressure chambers on opposite circumferential sides thereof adjacent the rotor, said sealing arcs and working chambers each extending for an arcuate distance substantially equal to but not less than the distance between two adjacent vanes, the outer ends of said vanes being subject to the respective pressures within said chambers while passing therethrough, and means for supplying to the inner ends of said vanes during substantially the entire time that the outer ends thereof are traversing the sealing arcs and the high pressure and working chambers fluid under pressure greater than but correlated to the pressure of the fluid in said high pressure chambers.

11. The combination of a rotary vane type fluid pressure device having a rotor including a plurality of vanes movable inwardly and outwardly thereof, a casing therefor including a track for guiding the vanes in their in and out movement and provided with a working chamber having high and low pressure chambers on opposite circumferential sides thereof adjacent the rotor, the outer ends of said vanes being sub-

ject to the respective pressures within said chambers while passing therethrough, a source of pressure fluid connected with said high pressure chamber, a source of pressure fluid under a pressure greater than said first mentioned source of pressure fluid connected to the inner ends of said vanes during at least a portion of each rotation of the rotor and means for maintaining said fluid of greater pressure connected to the inner ends of said vanes at a pressure correlated to the pressure of the fluid in said high pressure chamber.

12. In a rotary vane type fluid pressure device having a plurality of fluid sections, each fluid section comprising a working chamber and high and low pressure chambers on the opposite circumferential sides thereof, a two-part casing comprising axially separable casing members, a cavity in one of said casing members closed by the other casing member, a rotor positioned in said cavity and having a plurality of vanes movable radially inward and outward thereof, the outer ends of said vanes being subject to the respective pressures within said chambers while passing therethrough, a vane track for guiding said vanes in their in and out movement, one of said casing members having passages for conveying fluid to and from each of said fluid sections, the other of said casing members having passages for supplying fluid to the inner ends of said vanes, and means for maintaining fluid in the passages of said other casing member at a pressure related to but greater than the pressure of the fluid in said high pressure chambers.

13. In a rotary vane type fluid pressure device having a plurality of fluid sections, each fluid section comprising a working chamber and high and low pressure chambers on the opposite circumferential sides thereof, a two-part casing comprising axially separable casing members, a cavity in one of said casing members closed by the other casing member, a rotor positioned in said cavity and having a plurality of vanes movable radially inward and outward thereof, the outer ends of said vanes being subject to the respective pressures within said chambers while passing therethrough, a vane track for guiding said vanes in their in and out movement, one of said casing members having passages for conveying fluid to and from each of said fluid sections, the other of said casing members having passages for supplying fluid to the inner ends of said vanes while the outer ends of the vanes are passing through the high pressure and working chambers of each of said fluid sections, and means for maintaining fluid in the passages of said other casing member at a pressure related to but greater than the pressure of the fluid in said high pressure chambers.

14. In a rotary vane type fluid motor having a rotor including a plurality of vanes movable inwardly and outwardly thereof in a substantially radial direction, a casing therefor including a track for guiding the vanes in their in and out movement and provided with a plurality of working chambers each having high and low pressure chambers on opposite circumferential sides thereof adjacent the rotor, the outer ends of said vanes being subject to the respective pressures within said chambers while passing therethrough, means at one of the axial sides of said rotor for admitting pressure fluid to said high pressure chambers, and means at the other axial side of said rotor only for supplying to the inner ends

of said vanes fluid under pressure greater than but correlated to the pressure of the fluid in said high pressure chambers.

15. In a rotary vane type fluid pressure device having a rotor including a plurality of vanes movable inwardly and outwardly thereof, a casing therefor including a working chamber having high and low pressure chambers on opposite circumferential sides thereof, a track for guiding the vanes in their in and out movement, the outer ends of the vanes being subject to the respective pressures of the fluid within said chambers while passing therethrough, and means for continuously supplying to the inner ends of the vanes during substantially the entire time that the outer ends thereof are traversing the high pressure and working chambers fluid under pressure higher than the pressure in the high pressure chamber thereby urging the vanes into contact with the track independently of the action of centrifugal force, said means comprising a supply line, a power connection leading therefrom to the working chamber, a pressure connection leading from the supply line to the inner ends of the vanes, and a valve in the power connection arranged to cut off communication between the supply line and the working chamber when the motor is not operating and arranged to establish such communication only after a predetermined difference in pressure exists between the supply line and the working chamber.

16. In a rotary vane type fluid pressure device having a rotor including a plurality of vanes movable inwardly and outwardly thereof, a casing therefor including a working chamber having inlet and outlet chambers on opposite circumferential sides thereof and a track for guiding the vanes in their in and out movement, said working chamber extending for an arcuate distance substantially equal to but not less than the distance between two adjacent vanes, the outer ends of the vanes being subject to the respective pressures of the fluid within said chambers while passing therethrough, and means for continuously supplying to the inner ends of the vanes while they are traversing the inlet chamber fluid under pressure correlated to and higher than the pressure in the inlet chamber, thereby urging the vanes into contact with the track independently of the action of centrifugal force, said means comprising a supply line, a supply connection leading therefrom to the inlet chamber, a pressure connection leading from the supply line to the inner ends of the vanes, and a valve in the supply connection arranged to maintain a substantially constant differential pressure in the supply connection below the pressure in the supply line irrespective of the pressure in the supply line.

17. In a rotary vane type fluid pressure motor having a rotor including a plurality of vanes movable inwardly and outwardly thereof, a casing therefor including a sealing chamber, a working chamber and a track for guiding the vanes in their in and out movement, said working chamber having inlet and outlet chambers on opposite circumferential sides thereof and the outer ends of the vanes being subject to the respective pressures of the fluid within said chambers while passing therethrough, and means for supplying to the inner ends of the vanes, during substantially the entire time that the outer ends thereof are traversing the sealing chamber, the inlet chamber and the working chamber, fluid

under pressure correlated to and higher than the pressure in the inlet chamber, thereby urging the vanes into contact with the track independently of the action of centrifugal force, said means comprising a supply line, a power connection leading therefrom to the working chamber, a pressure connection leading from the supply line to the inner ends of the vanes, and a valve in the power connection arranged to maintain a substantially constant differential pressure in the power connection below the pressure in the supply line irrespective of the pressure in the supply line, said valve also being arranged to cut off communication between the supply line and the working chamber when the motor is not operating and arranged to establish such communication only after a predetermined difference in pressure exists between the supply line and the working chamber.

18. The combination of a rotary vane type fluid pressure device having a rotor including a plurality of vanes movable inwardly and outwardly thereof, a casing therefor including a track for guiding the vanes in their in and out movement and provided with a working chamber having inlet and outlet chambers on opposite circumferential sides thereof adjacent the rotor, the outer ends of said vanes being subject to the respective pressures within said chambers while passing therethrough, an auxiliary pump, means connecting the outlet of said pump to the inner ends of said vanes during at least the time that the outer ends of the vanes are passing through said inlet chamber, said pump delivering fluid in excess of the amount necessary to insure outward movement of said vanes into contact with said track, and escape means for said excess fluid including means regulating the escape of said excess therethrough to maintain the fluid supplied to the inner ends of said vanes under pressure exceeding by a substantially constant differential the pressure of the fluid in said inlet chamber irrespective of changes in the pressure thereof.

19. A rotary vane type fluid pressure device including a rotor, a plurality of vanes movable inwardly and outwardly of the rotor in vane slots formed therein, a casing for the rotor having a

track for guiding the vanes in their in and out movement and provided with two diametrically opposed working chambers, each having inlet and outlet chambers on opposite circumferential ends thereof adjacent the rotor, the outer ends of the vanes being subject to the respective pressures in the working chambers while passing therethrough, inlet and outlet ports for the inner ends of the vane slots arranged to connect successively with the vane slots while the outer ends of the vanes are passing through the inlet and outlet chambers respectively, an auxiliary pump arranged to supply pressure fluid to the inlet ports, means regulating the pressure of the fluid supplied by the pump to maintain in the inlet ports a pressure exceeding by a substantially constant amount the pressure of the fluid in the inlet chambers irrespective of changes in pressure of the fluid in the inlet chambers, and fluid outlet means for the outlet ports.

20. A rotary vane type fluid motor including a rotor, a plurality of vanes movable inwardly and outwardly of the rotor, a casing for the rotor having a track for guiding the vanes in their in and out movement and provided with two diametrically opposed sealing arcs and two diametrically opposed working chambers each having high and low pressure chambers on opposite circumferential sides thereof adjacent the rotor, said sealing arcs and working chambers each extending for an arcuate distance substantially equal to but not less than the distance between two adjacent vanes, the outer ends of the vanes being subject to the respective pressures within said chambers while passing therethrough, means for substantially equalizing the pressure of the fluid on the inner and outer ends of the vanes while the outer ends of the vanes are passing through the low pressure chambers, and means for supplying to the inner ends of the vanes while the outer ends thereof are passing through the high pressure chambers fluid under pressure greater than but correlated to the pressure of the fluid in the high pressure chambers, said last named means including an auxiliary pump arranged to provide the fluid of greater pressure.

CHARLES M. KENDRICK.
